US0D1108382S

(12) **United States Design Patent** (10) **Patent No.:** **US D1,108,382 S**
(45) **Date of Patent:** **** Jan. 6, 2026**

(54) **ROUND EXTENSION FORM**

(71) Applicant: **Ken Taylor**, Orangeville (CA)

(72) Inventor: **Ken Taylor**, Orangeville (CA)

(73) Assignee: **1000332602 ONTARIO INC.**,
Orangeville (CA)

(**) Term: **15 Years**

(21) Appl. No.: **29/962,265**

(22) Filed: **Sep. 11, 2024**

Related U.S. Application Data

(62) Division of application No. 29/735,856, filed on May 26, 2020, now Pat. No. Des. 1,051,868.

(57) **CLAIM**

The ornamental design for a round extension form as shown and described.

DESCRIPTION

FIG. 1 is a top perspective view of a round extension form showing the new design;

FIG. 2 is a bottom perspective view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof; and,

FIG. 8 is a bottom view thereof.

1 Claim, 5 Drawing Sheets
